SLUG CASTING MACHINE

William B. Ankarstran, Astoria, N. Y., assignor to
Mergenthaler Linotype Company, a corporation
of New York

Application April 20, 1938, Serial No. 203,079

15 Claims. (Cl. 199—59)

This invention relates to slug casting machines of the general organization represented in U. S. Letters Patent No. 436,532 to O. Mergenthaler, wherein a slug or type-bar is cast in a slotted mold against a composed line of matrices which produce the type characters thereon. In these machines, the molds are usually mounted in a vertical intermittently rotating carrier or disk which presents the slotted mold in a horizontal position for casting and thereafter carries it around to a vertical position in front of an ejector blade which pushes the cast slug from the mold. The mold disk is usually equipped with studs or pins which project from the face thereof and, during the slug-casting and slug-ejecting operations, are adapted to engage in recesses or sockets formed in a right-hand and a left-hand locating block mounted on the vise frame. Ordinarily, the left-hand block is floatingly attached to the vise frame by two screws or bolts, while the right-hand block is fixed to the vise frame by screws or bolts and dowel pins. Due to wear, the locating blocks have to be replaced from time to time and much difficulty has been experienced in drilling a new right-hand block so that the dowel pins by which it is fixed to the vise frame will be accurately centered with respect to the dowel holes already in the vise frame.

The present invention is directed to an improved form of locating block intended to obviate the foregoing and other difficulties, as will be fully described in the detailed description to follow.

In the accompanying drawing, the invention has been shown merely by way of example and in preferred form, but obviously many variations and modifications may be made therein which will still be comprised within its spirit. It is to be understood, therefore, that the invention is not limited to any specific form or embodiment, except insofar as such limitations are specified in the appended claims.

Referring to the drawing:

Fig. 1 is a plan view, showing in section the mold disk and vise frame with the improved locating block;

Fig. 2 is a side elevation, partly in section and partly broken away, showing the detail of the improved locating block; and

Fig. 3 is a perspective view of the mold block in disassembled condition.

As usual, the mold disk A, equipped with one or more molds A¹, is mounted for rotation upon the arm or support B projecting laterally from the mold slide (not shown) which is arranged to be reciprocated forwardly and backwardly in the

machine frame. The disk A is power operated for intermittent rotation in such manner that during casting the slotted mold A¹ is presented in a horizontal position and after casting carried around to a vertical position as shown in Fig. 1, where it registers with a pair of trimming knives C between which the slug is ejected from the mold by an ejector blade D. As is well known, the reciprocation of the mold slide is timed so as to move the disk A rearwardly when it is to be rotated to carry the slotted mold from casting to ejecting position, or vice versa, and to move the disk forwardly when in either of such positions, in one case to insure the close contact of the mold with the composed matrix line and in the other to locate the mold in immediate proximity to the trimming knives C. The mold disk is provided with diametrically opposed pins or studs A² which, when it is moved forwardly, engage in corresponding sockets in the right and left locating blocks A³, such engagement effecting and maintaining the proper registration of the mold with the cooperating devices. Ordinarily, the left-hand locating block A³ is made in two pieces A⁴ and A⁵ secured to the vise frame E by screws A⁶, the arrangement being such that the shanks of the screws A⁶ fit snugly in the openings A⁷ in the portion A⁴ of the block while the openings A⁸ in the portion of the block A⁵, through which the screws A⁶ pass, are larger in diameter than the shanks of the screws so that the section A⁵ is capable of floating in a lateral direction to compensate for slight changes which take place in the distance between the pins A² on the disk A as a result of expansion and contraction thereof. However, the right-hand locating block A³ heretofore has been made in one piece and fixed rigidly to the vise frame to locate the mold accurately with reference to the trimming knives C at all times.

According to the present invention, the right-hand locating block A³ is made in two pieces A⁹ and A¹⁰, primarily for adapting it as a replacement block although obviously being as well adapted for original installation.

Referring particularly to Figs. 2 and 3, the portion A⁹ of the block A³ is adapted to serve as a base fixed to the vise frame E by dowel pins A¹¹, the socket portion A¹⁰ of the block being adapted to be mounted on the base A⁹ and detachably secured by screws A¹² extending through the vise frame E and base A⁹ and being screwed into threaded openings A¹³ in the socket portion A¹⁰. In order to locate the socket portion A¹⁰ accurately to align with and receive the pins A² on

the mold disk, it is formed on its front face with a projection A¹⁴ adapted to seat in an opening A¹⁵ formed in the base A⁹. With this arrangement, when the socket portion A¹⁰ of the block A³ becomes worn, as frequently happens, it is merely necessary to replace this portion of the block,—the base A⁹, which is fixed to the vise frame and which is not subject to wear, remaining in place to receive the replacement socket portion of the block.

10 The socket portion A¹⁰ is formed also to serve as a templet for locating the base A⁹ on the vise frame E when the original installation of the base is made. To this end, the socket portion A¹⁰ is formed with two openings A¹⁶ and it, along with the base A⁹, is temporarily fastened to the vise frame E by the bolts A¹², whereby the holes A¹⁶ serve as guides for drilling holes A¹⁷ in the base A⁹ and vise frame E for the reception of the 15 dowel pins A¹¹. It is pointed out that the socket portion A¹⁰ need only be formed with the openings A¹⁶ when it is to be used for the original installation of the improved form of locating block since, as a replacement element, only the 20 socket portion A¹⁰ is required, the base A⁹ which has previously been fixed to the vise frame being unplaced.

Obviously, if desired, the invention might be applied in connection with the left-hand locating 25 block A³, but here it is a matter of choice whether the base A⁴ of the block is fixed to the vise frame E because some floating of the block is desirable.

As already stated, variations and modifications 30 of the invention may occur to those skilled in the art which will still be comprised within its spirit and, therefore, the invention is not limited to any 35 specific form or embodiment, except insofar as such limitations are specified in the appended claims.

40 Having thus described my invention, what I claim is:

1. In a slug casting machine, the combination 45 of a movable mold carrier, means arranged on the mold carrier for locating it to present the mold in operative position, a frame, and means arranged on the frame to cooperate with said locating means on the mold carrier, said cooperative means comprising a portion fixed to the frame and a detachable portion mounted thereon.

50 2. In a slug casting machine, the combination 55 of a movable mold carrier, means arranged on the mold carrier for locating it to present the mold in operative position, a frame, means arranged on the frame to cooperate with said locating means on the mold carrier, said cooperative means comprising a portion fixed to the frame and a detachable portion mounted thereon, and means for locating said detachable portion relatively to the fixed portion for alignment with the 60 locating means on the mold carrier.

65 3. In a slug casting machine, the combination 65 of a movable mold carrier, means arranged on the mold carrier for locating it to present the mold in operative position, a frame, means arranged on the frame to cooperate with said locating means on the mold carrier, said cooperative means comprising a portion adapted to be fixed to the frame and a portion adapted to be detachably mounted on the fixed portion, means for securing the fixed portion to the frame, and other means for fastening the fixed and detachable portions together.

70 4. In a slug casting machine, the combination 75 of a movable mold carrier, means arranged on the mold carrier for locating it to present the mold

in operative position, a frame, means arranged on the frame to cooperate with said locating means on the mold carrier, said cooperative means comprising a portion adapted to be fixed to the frame and a portion adapted to be detachably mounted on the fixed portion, means for locating the detachable portion relatively to the fixed portion for alignment with the locating means on the mold carrier, means for securing the fixed portion to the frame, and other means for fastening the fixed and detachable portions together.

5 5. A combination according to claim 1, wherein 15 said cooperative means is formed for use as a templet in locating its position on the frame.

6. A combination according to claim 1, wherein 20 the fixed portion is adapted to be secured to the frame by dowel pins and the detachable portion is formed for use as a templet in drilling the frame to receive the dowel pins.

7. A combination according to claim 1, wherein 25 the fixed portion is adapted to be secured to the frame by dowel pins and the detachable portion is adapted to be secured by bolts extending through the frame, and wherein the detachable member is formed with openings to accommodate 30 a drill so that it may be temporarily secured to the frame and used as a templet in drilling holes in the frame to receive the dowel pins.

8. A combination according to claim 1, wherein 35 the fixed portion is adapted to be secured to the frame by dowel pins and the detachable portion is adapted to be secured by bolts extending through the fixed portion and frame, and wherein the detachable member is formed with openings to accommodate 40 a drill so that it and the fixed portion may be temporarily secured to the frame and used as a templet in drilling holes in the fixed portion and frame to receive the dowel pins.

9. In a slug casting machine, the combination 45 of a frame, a mold disk movable fore and aft and rotatable to present a mold first in slug-casting position and then in slug-ejecting position, a plurality of locating pins carried by the mold disk, and a two-part socket member arranged on the 50 frame to receive one or another of said pins in the forward position of the disk when the mold is in slug-casting and slug-ejecting positions, said socket member comprising a base doweled to the frame and a socket portion detachably mounted on the base.

10. In a slug casting machine, the combination 55 of a frame, a mold disk movable fore and aft and rotatable to present a mold first in slug-casting position and then in slug-ejecting position, a plurality of locating pins carried by the mold disk, and a two-part socket member arranged on the frame to receive one or another of said pins in the forward position of the disk when the mold is in slug-casting and slug-ejecting positions, said 60 socket member comprising a base doweled to the frame and a socket portion detachably mounted on the base, whereby the socket portion may be replaced at will to the exclusion of the base.

11. In a slug casting machine, the combination 65 of a frame, a mold disk movable fore and aft and rotatable to present a mold first in slug-casting position and then in slug-ejecting position, a plurality of locating pins carried by the mold disk, and a two-part socket member arranged on the 70 frame to receive one or another of said pins in the forward position of the disk when the mold is in slug-casting and slug-ejecting positions, said socket member comprising a base doweled to the frame and a socket portion detachably mounted 75

on the base and secured to the frame, and said socket portion being formed with openings to accommodate a drill so that it and the base may be temporarily secured to the frame and used as a templet in drilling holes in the base and frame to receive the dowel pins.

12. In or for a slug casting machine of the "Linotype" class, a mold disk locating stud block comprising a base portion adapted to be fixed to the vise frame and a detachable socket portion adapted to be mounted on the base portion.

13. In or for a slug casting machine of the "Linotype" class, a mold disk locating stud block comprising a base portion adapted to be fixed to the vise frame and a detachable socket portion adapted to be mounted on the base, said base and detachable socket portions being formed with

interengaging means for locating the detachable socket portion relatively to the base portion.

14. In or for a slug casting machine of the "Linotype" class, a mold disk locating stud block comprising a base portion adapted to be fixed to the vise frame and a detachable socket portion adapted to be mounted on the base portion, the detachable portion being formed for use as a templet to locate the position of the base portion on the vise frame.

15. In or for a slug casting machine of the "Linotype" class, a mold disk locating stud block comprising a base portion adapted to be dowled to the vise frame and a detachable socket portion adapted to be mounted on the base portion.

WILLIAM B. ANKARSTRAN.
